(57) CLAIM

The ornamental design for a garment with a cross strap, as shown and described.

DESCRIPTION

FIG. 1 is a perspective view of the garment with a cross strap;

FIG. 2 is a front view thereof;

FIG. 3 is a rear view thereof;

FIG. 4 is a left side view thereof;

FIG. 5 is a right side view thereof;

FIG. 6 is a top plan view thereof; and,

FIG. 7 is a bottom plan view.

The broken lines in the drawings depict environmental subject matter of a garment with a cross strap only and form no part of the claimed design.
